UNITED STATES PATENT OFFICE.

ANDREW JANER, OF FLUSHING, NEW YORK.

ASH TRAY.

Application filed February 21, 1925. Serial No. 10,777.

REISSUED

To all whom it may concern:

Be it known that I, ANDREW JANER, a citizen of the United States, and a resident of Flushing, county of Queens, city and State 5 of New York, have invented certain new and useful Improvements in Ash Trays, of which the followin^r is a specification sufficient to enable those skilled in the art to which the invention appertains to utilize the 10 same.

My improvements relate to the class of trays designed for the use of smokers of cigars and cigarettes, particularly the latter, the object being to afford a simple, sanitary, unitary structure adapted to the various requirements and convenience of users, easily cleaned, and insuring ample protection against extraneous deposit of ash, spark, or remnant—the invention consisting 15 in the specific construction and arrangement of parts described and claimed, and a distinctive feature being a central rest dais extending above the rim of the tray and formed with concentric ridges for the support of a cigar or cigarette, with concavities 20 between said supporting ridges, which admit of air circulation around and under a cigar or cigarette placed on the dais; incidental features relating also to the configuration 25 of the underside of the device, whereby it is adapted to embellishment when made of transparent or translucent material, all as hereinafter fully set forth.

In the accompanying drawings I illustrate 30 a practical embodiment of the essential features of my invention, although I do not restrict myself to the identical configuration shown by way of exemplification, since modifications may be resorted to in minor 35 details of construction and shape with like results, and without departing from the spirit and intent of my invention in this respect.

With this understanding:—

Fig. 1, represents a top view or plan of my 40 improved ash tray;

Fig. 2, is an edge or side view thereof;

Fig. 3, a section thereof taken upon plane 45 of line 3—3, Fig. 1;

Fig. 4, is a view of the underside of the tray.

My ash tray is preferably, although not necessarily, made of transparent or translucent material, as for instance glass, so 50 that embellishment imposed on the underside thereof will be visible from above; and

for this reason the circumferential supporting or bearing edge *e*, of the base protrudes beyond the plane *p*, of bottom surface thereof, as shown more particularly in Fig. 3, of 60 the drawings.

The upper part of the central dais *d*, extends above the plane of the upper edge of the concentric rim *r*, of the tray, said dais portion of the device being preferably of 65 truncated conoidal form, and merging curvilinearly into the bottom portion *b*, of the tray, as do also the inner sides of the rim *r*, all as shown more particularly in said Fig. 3, of the drawings. This curvilinear structure 70 facilitates cleaning while rendering the device symmetrical in appearance.

The circular edge *d'*, of the upper surface of the dais *d*, is formed with a plurality of concave seats *s*, *s*, preferably four in number, as shown in Fig. 1, of the drawings, the same being equidistant as related to each other so as to be opposed in alignment, 75 diametrically considered.

Concentric with the circular edge *d'*, of 80 the dais *d*, the top surface thereof is formed with an annular ridge *a*, the top plane of which is below that of the peripheral seats *s*, *s*, as indicated by the dotted line *x*, *x*, Fig. 3, and between the said seats *s*, *s*, and 85 the annular ridge *a*, the upper surface of the dais is formed with an annular concavity *c*, the central space *c'*, within the annular ridge being also concave.

The interior *i*, of the dais *d*, is also in 90 the form of a concavity, upon the curvilinear surface of which may be imposed embellishment that will be visible through the sides and the upper surface of said dais *d*, provided the tray is made of transparent or 95 translucent material.

It will thus be readily understood that a cigar or cigarette placed upon the dais *d*, will not rest upon a flat surface, but upon a plurality of supporting ridges with intervening depressions or concavities which will admit of circulation of air underneath the article so placed. This feature is of particular importance in so far as cigarettes are concerned, which, if placed upon a flat 105 surface when alight are subject to "sweat", thereby impairing the taste and flavor of subsequent smoking, and even resulting in the extinguishing of the light.

It is to be understood that the circum- 110 scribing rim *r*, is of such extent and diameter as related to the central dais *d*, as

to insure the deposit and reception, within the tray, of any remnant or any spark or ash detached from a cigar or cigarette placed, as stated, on the top of the dais *d*; 5 and that the height of said dais above the rim precludes the possibility of resting a cigar or cigarette upon and between it and the dais.

In other words, the cigar or cigarette can 10 be properly supported only on the dais, and when so supported its extremities are necessarily within the circumferential rim, no matter what the position of rest on the top of the dais may be.

15 What I claim as my invention and desire to secure by Letters Patent, is:—

1. An ash tray of the character designated, formed with a circumscribing rim and a central dais extending above said rim, the 20 upper surface of said dais being formed with a circular ridge having a plurality of seats, and with a concentric annular ridge, and also with a concavity between said ridges, the plane of said central concentric 25 annular ridge being below that of the series of seats in the circular rim of the dais, for the purpose and substantially in the manner set forth.

2. An ash tray of the character design- 30 nated, formed with a circumscribing rim and a central dais extending above said rim,

the upper surface of said dais being formed with a circular ridge having a plurality of seats, and with a concentric annular ridge, and also with a concavity between said 35 ridges, the plane of said central concentric annular ridge being below that of the series of seats in the circular rim of the dais, the underside of said central dais being formed with a concavity, for the purpose 40 and substantially in the manner set forth.

3. An ash tray of the character designated, formed with a circumscribing rim and a central dais extending above said rim, the upper surface of said dais being formed 45 with a circular ridge having a plurality of seats, and with a concentric annular ridge, and also with a concavity between said ridges, the plane of said central concentric annular ridge being below that of the series of seats 50 in the circular rim of the dais, the underside of said central dais being formed with a concavity, and the underside of the tray with a flat annular surface around said concavity in the dais, said annular flat surface 55 being in a plane within that of the bearing edge of the base, for the purpose and substantially in the manner set forth.

ANDREW JANER.
